Milton D. Grindall
ATTORNEY

UNITED STATES PATENT OFFICE.

JAMES T. REED, OF AKRON, IOWA, ASSIGNOR OF ONE-HALF TO SAMUEL D. CARNEY,
OF SIOUX CITY, IOWA.

LEVEL.

Application filed November 2, 1920. Serial No. 421,392.

To all whom it may concern:

Be it known that I, JAMES T. REED, a citizen of the United States, and a resident of Akron, in the county of Plymouth and State 5 of Iowa, have invented certain new and useful Improvements in Levels, of which the following is a specification.

My invention has for its primary object the production of mechanic's level, embodying certain novel features of construction and arrangement of parts, rendering it thoroughly dependable and accurate and instantly readable.

Furthermore, my invention contemplates a 15 mechanics' level which is instantly readable from either side or from above.

Still another object of the invention is the production of a level embodying improved adjusting means.

20 Still another object of the invention is the production of an improved mechanics' level, simple and inexpensive in construction, yet durable, accurate, and thoroughly dependable.

25 These and other objects and advantages I successfully attain in the embodiment hereinafter described, defined in the appended claims and illustrated in the accompanying drawings, which form a part of this application and in which like characters of reference indicate corresponding parts in both views, of which,

30 Fig. 1 is a fragmentary central, vertical section of the level, constructed in accordance with the invention, and

35 Fig. 2 is a fragmentary plan thereof, a part being shown in horizontal section.

While I have illustrated and hereinafter described a preferred embodiment of the invention, I would not be understood as being 40 limited to such specific construction, for various alterations and modifications may be made in the details of construction and arrangement of parts herein disclosed without departing from the spirit and scope of the invention as defined in the appended claims.

Referring now to the illustrations, the device consists, essentially, of a straight-edged body or stock, 3, having an intermediate 45 transverse circular opening, 4, in which I insert a short bushing, 5, within which is rotatably mounted a cylindrical ring 6, at one end of which is a flat ring, 7, preferably an integral part of the ring, 6, and carrying 55 a distance from its free edge a flange, 8,

spaced a distance from, and relatively shorter than, the flat ring, 6.

Longitudinal displacement of the rings, 6, is prevented by retaining rings, 9, at the ends of the bushing, 5.

60 The upper edge of the stock, 3, is slotted, as at 10, into the opening, 4, the portion of the bushing, 5, and ring, 6, co-incident with the slot, 10, being cut away to reveal the flange, 8, as clearly shown in Figure 1. The 65 slot is preferably covered by a flush escutcheon plate, 11, suitably secured to the stock and provided with an intermediate slot, 12, co-incident with the slot, 10, and below the plate, 11, is a transparent plate, 13, embedded in a gain in the stock to prevent the entrance of foreign material through the slot, 10. On opposite sides of the stock are transparent plates, 14, which close the opening, 4, and are secured in gains, 15, in the stock 70 by means of retaining rings, 16, suitably secured to the stock.

75 Extending co-axially through the ring, 6, is a spindle, 17, having its ends rotatably supported by the transparent plates, 14; the 80 said spindle, 17, carries indicating hands, 18, the lower ends of which are counterweighted, as at 19. The said hands are positioned on opposite sides of the ring, 7, and register with scales, 20, on both sides of the 85 ring, 7, and preferably graduated in degrees reading in both directions 90 degrees from zero at the top and bottom.

85 The end portion of one of the hands, 18, is bent laterally, as at 21, to swing in the 90 space between the ring, 6, and flange, 8, the periphery of the flange, 8, being provided with a graduated scale, 22, co-incident with the slot, 10.

95 It will now be clear that the counter-weighted hands, 18, always point directly upwardly, and when used as a level the scale may be instantly read from either side, or downwardly through the slot, 10, and when used as a plum with the stock turned at 100 right angles so that its bottom edge, properly speaking, is vertically disposed, the scale may be read from either side.

105 I provide simple adjusting means, preferably consisting of a toothed segment, 23, secured to the ring, 6, and projecting radially through a slot, 24, in the bushing, 5, and into a notch, 25, in the stock, communicating with the opening, 4. The segment, 23, is intermeshed with a worm, 26, positioned 110

in the notch, 25, and having a shank, 27, rotatable in a bore, 28, in the stock, communicating with the notch, 25, the upper end portion of the shank, 27, being provided with a slotted head, 29, counter-sunk in the escutcheon plate.

Longitudinal movement of the worm is prevented by a suitable member, 30, embedded in the stock below the escutcheon plate, and projecting into an annular groove, 31, in the shank, 27. By means of this construction, the graduated circular members within the bushing may be accurately adjusted in either direction by rotation of the worm in the proper direction.

Having thus described my invention, what I claim as new and desire to secure by Letters Patent of the United States is:

1. A device of the class described comprising a stock having an opening therein, a cylindrical ring in the opening, a flat ring adjacent one end of the cylindrical ring, a lateral annular flange on the flat ring, disposed within and spaced from the cylindrical ring, counterweighted hands pivoted coaxially with the rings and positioned on opposite sides of the flat ring, indicating points on the flat ring with which the hands register, one of said hands having a horizontal portion to swing in the space between the flange and cylindrical ring, and indicating points on the periphery of the flange with which said horizontal hand portion registers.

2. A device of the class described comprising a stock having an opening therein, a cylindrical ring in the opening, a flat ring

adjacent one end of the cylindrical ring, a lateral annular flange on the flat ring, disposed within and spaced from the cylindrical ring, counterweighted hands pivoted coaxially with the rings and positioned on opposite sides of the flat ring, indicating points on the flat ring with which the hands register, one of said hands having a horizontal portion to swing in the space between the flange and cylindrical ring, and indicating points on the periphery of the flange with which said horizontal hand portion registers, a segment of the cylindrical ring being cut away to reveal said indicating points on the flange.

3. A device of the class described comprising a stock having an opening therein, a cylindrical ring in the opening, a flat ring adjacent one end of the cylindrical ring, a lateral annular flange on the flat ring, disposed within and spaced from the cylindrical ring, counterweighted hands pivoted coaxially with the rings and positioned on opposite sides of the flat ring, indicating points on the flat ring with which the hands register, one of said hands having a horizontal portion to swing in the space between the flange and cylindrical ring, and indicating points on the periphery of the flange with which said horizontal hand portion registers, a segment of the cylindrical ring being cut away to reveal said indicating points on the flange, and the stock having an upper observation opening coincident with said cut away segment.

In testimony whereof, I have hereunto set my hand this 28th day of October, 1920.

JAMES T. REED.
